US0D1042933S

(12) **United States Design Patent** (10) Patent No.: **US D1,042,933 S**
(45) Date of Patent: ** Sep. 17, 2024

(54) **CEILING LIGHT**

(71) Applicant: **Lucifer Lighting Company**, San Antonio, TX (US)

(72) Inventors: **Anuj Maloo**, San Antonio, TX (US); **Benjamin Karpen**, San Antonio, TX (US); **Jack Reilly**, San Antonio, TX (US)

(73) Assignee: **Lucifer Lighting Company**, San Antonio, TX (US)

(**) Term: **15 Years**

(21) Appl. No.: **35/516,224**

(22) Filed: **Dec. 2, 2022**

(80) **Hague Agreement Data**

Int. Filing Date: **Dec. 2, 2022**

Int. Reg. No.: **DM/226422**

Int. Reg. Date: **Dec. 2, 2022**

Int. Reg. Pub. Date: **Feb. 10, 2023**

(51) **LOC (14) Cl. 26-05**

(52) **U.S. Cl.**

USPC **D26/72; D26/61**

(58) **Field of Classification Search**

(57) **CLAIM**

The ornamental design for a ceiling light, as shown and described.

DESCRIPTION

1. Ceiling light

1.1 : Perspective view in 1st position

1.2 : Front view in 1st position

1.3 : Back view in 1st position

1.4 : Right view in 1st position

1.5 : Left view in 1st position

1.6 : Top view in 1st position

1.7 : Bottom view in 1st position

1.8 : Perspective view in 2nd position

1.9 : Front view in 2nd position

1.10 : Left view in 2nd position

1.11 : Right view in 2nd position

1.12 : Back view in 2nd position

1.13 : Top view in 2nd position

1.14 : Bottom view in 2nd position

1.15 : Perspective view in 3rd position

1.16 : Front view in 3rd position

1.17 : Left view in 3rd position

1.18 : Right view in 3rd position

1.19 : Back view in 3rd position

1.20 : Top view in 3rd position

1.21 : Bottom view in 3rd position

(Continued)

A ceiling light is shown in three positions to illustrate the range of motion with one possible intermediate position; The ceiling light is infinitely adjustable between the straight down position in the first group of representations and the ninety degree position in the last group of representations; No protection is sought for the features of the designs indicated by broken lines shown in the representations; in the representations, the jagged broken lines and the curly brackets show a symbolic break in length; Any portions between such jagged lines form no part of the claimed design.

1 Claim, 17 Drawing Sheets

(58) Field of Classification Search

CPC F21S 8/00; F21S 8/003; F21S 8/04; F21S 8/043
